[57] CLAIM

The ornamental design for a liposuction patient positioning support, as shown and described.

DESCRIPTION

FIG. 1 is a top front perspective view of the liposuction patient positioning support of the present invention showing my new design;

FIG. 2 is a top plan view thereof;

FIG. 3 is a bottom plan view thereof;

FIG. 4 is a side elevational view thereof, the opposite side elevational view being identical thereto;

FIG. 5 is a rear end elevational view thereof; and,

FIG. 6 is a front end elevational view thereof.
